RIBBON LOOM

William Harris, Paterson, N. J.

Application June 26, 1939, Serial No. 281,112

3 Claims. (Cl. 139—138)

In a well-known type of loom, as a ribbon loom, a rack reciprocatory lengthwise of and in the back-and-forth-movable batten drives the shuttles, as through pinions. A system to transmit reciprocation to the rack includes flexible connections, as straps, and a rotary guiding means housed within with its axis substantially horizontal and crossing the batten and up to which said connections extend and around which said connections extend and around which in opposite directions they then extend and exist attached to the rack. Suitable means, removed from the batten, as a suitably and constantly rotated double-crank to which the connections are respectively connected at opposite sides of its axis of rotation, imparts pulls to said connections independently of each other and in alternation, that is to say, so that a pull is exerted on one connection or the other each time the batten structure is back and the warp sheds open to receive the shuttles.

The construction is such that, since said connections reach up into the space in the batten in which said guiding means is located and since said space is necessarily of limited width and taking into account the back and forth movements of the batten relatively to a guide for said connections having fixed location, as on the floor near the lay-swords for supporting the batten, the connections in their own back and forth travel wipe against the batten and so become chafed and sooner or later cease to be any longer serviceable and have to be replaced by new ones.

The object of this invention is so to improve the construction of a loom of this type as to eliminate all contact of the lengthwise traveling connections with any relatively fixed part of the batten structure and the consequent wear thereof.

40 In the drawing:

Fig. 1 is a side elevation of so much of the improved loom as is necessary to illustrate the invention;

Fig. 2 is a front elevation of that end of the batten structure to which the invention is applied showing certain parts present in accordance with the invention;

Fig. 3 shows the batten structure and other parts in section in the vertical plane of the axis of cylinder 18, which and associated parts appear in elevation;

Fig. 4 shows the cylinder in transverse section and, in elevation, the rack and the connections between it and the cylinder; and

55 Fig. 5 is a side elevation of a fragment of said

cylinder and the connections 23 on a larger scale.

The batten structure includes, as usual, the usual beam 1 constituting the batten, supported by lay-swords 1a so as to be movable forward 5 or to the right and back, and a top rail 2 parallel with the batten and which is supported by end walls, such as 3, and by the usual spaced blocks, not shown, in the grooves of which the shuttles are guided and move.

In grooves 4 in the batten and rail is reciprocatory the rack which here comprises racks proper 5 in the respective grooves and lapped plates 6 secured to the respective racks proper and held together by a clamp 7 and screws 7a. 10

According to my invention an oscillating cylinder is to be journaled in the batten structure so as to cross the rack and project rearwardly from said structure. Said cylinder is to be operatively connected with the rack to form therewith a back-and-forth-movable train and it is to be oscillated by flexible connections extending to its projecting portion in an up and down direction and also extending in opposite directions around and attached thereto, wherefore, 20 taking into account the back and forward movements of the batten structure, said projecting portion of the cylinder is plain or throughout of one diameter so that the connections in winding on the cylinder can do so spirally without 25 chafing each other or any part of the cylinder. In the present example the portion of the cylinder which crosses the rack is below the same and actually housed within the batten.

As here shown the batten is formed with a recess 8 which is open at least rearwardly and is here closed at the front by a wall 9 forming an integral part of the batten. Secured to the front face of the batten by screws 10 is a plate 11 arranged opposite recess 8. This plate and wall 9 have superposed holes 12—13. In the lower hole is fitted and fixed by a pin 14 the forward end of a bar 15 which at its rear end has an upstanding fixed head 16, and projecting 40 forwardly from the head above the bar and fast to the head is a shaft 17 whose forward end fits the hole 12. Otherwise stated, parts 15—16—17 form a forked member which, with plate 11, forms one part of a two-part bearing support for the 45 mentioned cylinder.

The cylinder is indicated 18, being journaled on shaft 17 and reaching from wall 9 of the batten to head 16; it is thus partially housed in recess 8 and also projects rearwardly of the 50 55

batten. Its projecting portion is plain for its whole length.

Any expedient for imparting reciprocation to the rack from the cylinder, when oscillated, may be provided. In this example there are two flexible elongated connectors 19 extending in opposite directions from the cylinder to the rack and secured to the latter as at 20; here to avoid chafing each other they exist as distinct or separate elements or straps arranged in two vertical planes and secured to the cylinder at 21.

For oscillating the cylinder let 22 be a double-crank assumed to be constantly rotated in one direction from some going part of the loom, as well known in this art: see, for instance, the patent to Sands No. 1,138,418. To diametrically opposite points of this double-crank are pivotally connected the ends of flexible straps 23 which, as also known, extend under suitable guiding means 24, as pulleys mounted in a suitable bracket 25 supported on the floor near the lay-swords. The other ends of these straps extend up on opposite sides of the mentioned bearing support and of the cylinder and, extending around the latter in opposite directions, are secured thereto, as at 26. In this example they are attached to the cylinder when the batten is in its extreme forward position. Each of these connections is related to the cylinder in a peculiar way, to wit:

When the batten moves back and the warp sheds are opened the rack must be driven one way or the other to pass the shuttles through the sheds. Whichever strap 23 is active at this time to drive the rack winds of course around the cylinder, and it should so wind that it will not wrap around itself, thus not only causing chafing and wear thereof but irregular motion of the rack. Hence, according to this invention and the said example each strap is wound around the cylinder so that its end is constantly at the rear of the spiral thereof more or less formed, that is to say, even when the batten is fully forward, or substantially as in Fig. 1. Otherwise stated, the guide 24 being so positioned that a vertical plane tangent to its forward or delivery side cuts the cylinder when in its forward position, when the cylinder is in that position each strap exists wound more or less therearound so that its end is rearward of the helical formed. Therefore each time, on a backward movement of the cylinder, the latter causes a winding of either strap thereon such winding proceeds forwardly and thus so as to wind the strap directly on the cylinder or without wrapping of the strap around itself. The straps being initially associated with the cylinder so that one is forward of the other, as one winds the other unwinds and so whatever spacing exists initially between the portions thereof depending from the cylinder are maintained constant. And they are initially so arranged (to wit, in what I herein term their "spacing") that on a complete revolution of the cylinder in either direction one

will not climb or wrap the other. The portion of the cylinder around which the straps wrap is plain or without flanges or the like which they might climb or rub against.

According to my invention, therefore, there is not only no rubbing of the straps against fixed parts of the batten structure but no winding of the straps on themselves with consequent undue wear thereof and irregular action of the rack.

Having thus fully described my invention, what I claim is:

1. In a loom of the class described, the combination, with a back-and-forth-movable batten-including structure and a rack reciprocatory lengthwise of and in said structure, of an oscillatory element journaled in said structure on a substantially horizontal axis crossing the rack and being operatively connected with the rack to move the same back and forth in synchrony with respective back and forth rotations of said element and having a plain substantially cylindrical concentric portion thereof projecting generally horizontally in one direction crosswise of the batten structure, flexible connections to be alternately pulled and extending in opposite directions around and attached to said portion of said element, and guiding means for the connections arranged to direct the same to said element in proximity to a vertical plane cutting the axis of the latter when the batten structure is forward, each connection existing helically wound around said element and in the herein-defined spacing from the other element.

2. In a loom of the class described, the combination of a reciprocatory batten-including structure and the shuttle-driving rack movable therein lengthwise thereof, the batten having a recess open at the rear side thereof, a rotary element journaled in said structure on an axis crossing the rack generally horizontally, said element having a portion within said recess and operatively connected with the rack to move the same back and forth in synchrony with respective back and forth rotations of said element and a portion protruding from said recess, and means to rotate said element back and forth including flexible connections wound in opposite directions around the protruding portion of said element.

3. In a loom of the class described, the combination of a reciprocatory batten having a recess open at one side thereof, a shuttle-driving rack reciprocatory in and lengthwise of the batten, a bearing structure fast to the batten and having a bearing portion whose axis crosses the rack generally horizontally, a rotary element journaled on the bearing portion and projecting in one direction from the batten and operatively connected with the rack to move the same back and forth in synchrony with respective back and forth rotations of said element, and means to rotate said element back and forth including flexible connections wound in opposite directions around the projecting portion of said element.

WILLIAM HARRIS.
